UNITED STATES PATENT OFFICE

2,445,158

HOSPITAL BED

Frank Sparhawk, Akron, Ohio

Application April 18, 1946, Serial No. 663,176

3 Claims. (Cl. 5—60)

1

This invention relates to bed construction, and more particularly to beds designed for use in hospitals, the primary object of the invention being to provide a mattress or mattress support embodying a plurality of movable sections so constructed and arranged, that certain sections may be elevated while certain other sections are lowered, thereby changing the locations of the portions of the mattress contacting the patient, for the comfort of the patient.

Another object of the invention is to provide a vertically adjustable frame supported within the bed, and so constructed that the frame may be elevated to lift the patient above the bed or mattress, the patient assuming an inclined position if desired.

With the foregoing and other objects in view which will appear as the description proceeds, the invention consists of certain novel details of construction and combinations of parts, herein-after more fully described and pointed out in the claims, it being understood that changes may be made in the construction and arrangement of parts without departing from the spirit of the invention as claimed.

Referring to the drawings

Figure 1 is a longitudinal sectional view through a bed constructed in accordance with the invention, the plane of section indicated by line 1—1, Fig. 2.

Figure 2 is a sectional view taken on line 2—2 of Figure 1.

Figure 3 is an end elevational view of the bed, portions of the foot posts being broken away to illustrate the supporting screws of the vertically adjustable frame.

Figure 4 is a perspective view of the frame, the adjustable back and leg rests thereof being shown in their raised positions.

Figure 5 is an enlarged fragmental elevational view illustrating the leg rest securing means.

Figure 6 is a sectional view taken on line 6—6 of Figure 2.

Referring to the drawings in detail, the bed comprises the usual side rails 5 which connect the head piece 6 and foot piece 7 of the bed, in the usual and well known manner.

The posts of the bed indicated at 8, are hollow and are formed with bearings 9 arranged therein, which bearings accommodate the vertical threaded shafts 10.

At the lower ends of the shafts 10 are secured pinions 11 that mesh with the pinions 12 that are secured at the ends of the horizontal shafts 13, the pinions 11 also meshing with the pinions 15

2

14 secured to the ends of the horizontal shaft 15 that is mounted within one of the hollow side rails 5.

5 A crank shaft 16 to which the crank 17 is connected, extends into the post 8, at one corner of the bed, the shaft being provided with the beveled pinion 18 that meshes with one of the pinions 11. Thus it will be seen that due to this construction, by operating the crank 17, the vertical threaded shafts 10 will be rotated simultaneously. Supported by the vertical threaded shafts 10, is a vertically adjustable frame embodying end bars 19 which are connected by means of the spaced parallel main bars 20, the frame being 10 of a size to fit over the upper portion of the bed. This frame is formed with an opening 45 disposed centrally thereof to permit the convenient use of a bed pan by the patient.

15 The bars 20 are formed with elongated openings 21 in which the pins 22 operate, the pins 22 extending laterally from the lower ends of the brace rods 23 that connect with the pivoted frame 24. The pins 22 of the brace rods 23 at the ends of the pivoted frame 24, are threaded to 20 receive the wing nuts 25, whereby the frame 24 may be held in various inclined positions, for the comfort of the patient.

25 The pivoted frame at the foot of the bed comprises a plurality of pivoted bars 26 which are 30 connected with the main bars 20, the outer or free ends of the bars 26 being connected by means of the rod 27. Supporting rods 28 have pivotal connection with the end bars 26 and extend downwardly through the pivoted keepers 29 35 mounted within the brackets 30, there being provided securing bolts 31 for securing the rods 28 in their positions of vertical adjustment.

30 Thus it will be seen that due to this construction, the pivoted frames or supports of the main frame 19, may be adjusted vertically so that the patient may rest in a comfortable position.

40 The reference character 32 indicates bearings that are secured to the end bars 19 of the main frame, the bearings being formed with internal threads to accommodate the shafts 10 to the end that when the shafts 10 are rotated, the main frame will be moved longitudinally thereof, so that the main frame may be adjusted to various heights.

45 In addition to the vertically adjustable frame, the bed comprises a plurality of spaced longitudinal bars 33 which have their ends secured to the head bars 33' and bars 34' of the foot piece 7 of the bed. These bars 33 are formed with 50 openings arranged in spaced relation with re-

spect to each other, which openings accommodate the rods 34 of the heads 35, the lower ends of the rods being supplied with rollers 36.

Directly under the bars 33 are horizontal shafts 37 which have their ends mounted in bearings 38 secured to the cross bars of the head and foot pieces of the bed. Cams 39 are secured to these shafts, and are designed to engage the rollers 36, so that as the cams rotate with the shafts 37, the rods 34 and heads 35 will be moved vertically.

The movement of the shafts 37 is accomplished by the operating rod 40 which has connection with the cranks 41 that are secured to the ends of the shafts 37, the operating rod 40 being connected with the crank handle 42, so that the shafts 37 will be moved simultaneously. The crank handle 42 is held in its positions of adjustment by means of a pin which extends therefrom, the pin being designed to be positioned in one of the openings 43 of the arcuate shaped keeper 44.

It might be further stated that alternate cams 39 of the shafts 37, are offset, so that when the shafts 37 are operated, certain of the rods 34 and heads 35 will be elevated, while certain other rods 34 and heads 35 will be lowered, as clearly shown by Figure 1 of the drawings. In this way it will be noted that the supporting surface for the mattress or patient, may be varied changing the point of contact between the bed and patient, for the comfort of the patient.

What is claimed is:

1. A hospital bed comprising a supporting surface embodying a plurality of independent supporting members, a plurality of spaced longitudinal bars having openings, rods secured to the supporting members and being extended through the openings of the bars, rollers mounted on the lower ends of the rods, shafts disposed under the longitudinal bars, cams secured to the shafts directly under said rollers, a crank for operating the shafts, whereby the rods and supporting members are moved vertically.

2. A hospital bed comprising a supporting surface embodying a plurality of independent supporting members, a plurality of spaced longitudinal bars having openings, rods secured to the supporting members and being extended through the openings, parallel horizontal shafts mounted under the bars, rollers on the rods, cams on the shafts engaging the rollers, whereby rotary movement of the cams moves the supporting members vertically, said cams being offset with respect to each other whereby alternate supporting members are elevated above the adjacent supporting members.

3. A hospital bed comprising a frame, a plurality of transversely spaced parallel bars having openings formed therein, a supporting surface embodying a plurality of supporting members, rods secured to the supporting members and extending through the opening of the bars, shafts mounted under the bars, cams mounted on the shafts to rotate therewith, operating means for transmitting movement of the cams to the rods and supporting members, said operating means embodying rollers secured to the rods and resting on the cams, said cams being so constructed and arranged that alternate supporting members are elevated, while certain other supporting members are lowered.
